NEWTON K. BOWMAN, OF BOWDIL, OHIO

CUTTER-CHAIN BLOCK

Application filed June 10, 1932. Serial No. 616,535.

This invention relates to cutter chains of mining machines and has special reference to the bit block and the means for securing the bit thereon. Mining machine cutter chains are composed of alternate bit blocks and coupling links which are pivotally connected so that they form a continuous endless chain which is driven around a supporting cutter bar so that bits mounted upon the bit blocks will be caused to engage and form clefts in a bank of coal to facilitate subsequent breaking down of the shelf of coal. Removable and reversible bits have been heretofore provided and have been held between two clamping members which are secured to the bit block and a securing screw has been provided to aid the bit-holding members in resisting the thrust to which the bits have been subjected in action, but it has been found that with the screw disposed substantially at a right angle to the bit the thrust was received upon the end of the screw and the screw tended to work loose and failed to maintain a lasting engagement with the parts which were secured. According to the present invention, the securing bolt or screw is so disposed and the cooperating parts are so formed that friction will be utilized to resist the thrust and the strain upon the bolt will, consequently, be lessened. The invention is illustrated in the accompanying drawing in which Figure 1 is a view, partly in section and partly in side elevation, of a bit block and a bit secured thereon according to the present invention.

Fig. 2 is a top plan view of the same. The bit block 1 is constructed with openings 2 adjacent its ends whereby it may be pivotally attached to coupling links, indicated at 3 in dotted lines, to be fitted in a chain, and each bit block is provided, at its inner side, with a tooth 4 adapted to engage sockets in a driving wheel and guide grooves in a cutter bar whereby the chain will be guided and supported. At its outer side or edge, the bit block is formed with an extension or abutment 5 having a recess in one side adapted to receive a holding member 6 having an enlarged foot 7 engaging in a recess 8 in the block which recess extends into the face of the abutment extension 5 so that

the bit-receiving wedge or holder 6 will be retained in the bit block against outward thrust. The inner face of the abutment 5 is provided with a groove 9 suitably shaped to provide a seat for the reversible removable bit 10, the end of the bit projecting beyond the seat, as clearly shown in Fig. 1, so that it may properly engage and cut into the bank of coal. Between the abutment 5 and the opposite end of the bit block, the outer edge or face of the block is straight to provide a support for the tapered clamping block or wedge 11 which has its end member suitably shaped to provide a seat for the lower end or corner of the bit, as clearly shown in Fig. 1. The longer side of the clamping block or wedge 11 seats against the outer edge or face of the bit block while the outer side of the wedge converges toward the block from the bit. An obliquely disposed opening 12 is formed through the clamping block 11 and a threaded socket or bore 13 is formed in the body of the bit block and aligned axially with said opening, the diameter of the opening being greater than the opening of the threaded bore or socket in order to permit some adjustment of the clamping block. A securing bolt 14 is inserted through the opening 12 and has its threaded shank engaged in the threaded socket or bore 13, as clearly shown in Fig. 1, a washer 15 being placed over the outer end of the opening or hole 12 under the head of the bolt so as to provide a firm bearing for the bolt head, as will be understood. In assembling the parts, the bit seat or holder 6 is first engaged in the bit block so that the heel of its foot 7 will engage in the notch provided therefor in the abutment member 5. The bit is then placed in position, seating within the member 6, and the clamping block 11 is then brought into engagement with the bit, whereupon the clamping bolt 14 is turned home so as to firmly hold the parts together. It will be understood that, in use, the cutter chain is moved in such direction that the projecting end or point of the bit 10 is moved along the bank of coal so as to score the same. The resistance offered by the coal to the travel of the bit tends to cause the inner end

of the bit to move away from the seat or holding member 6 and this tendency is resisted by the clamping block 11. In the present arrangement, the block is secured in such a manner that there is a very high degree of friction between the opposed surfaces of the clamping block and the bit block which resists the tendency of the bit to rock in the stated manner so that the bit will be very firmly held to its work. The thrust is only indirectly received by the clamping bolt and the tendency is to cause the clamping block 11 to wedge more tightly between the bolt head or the washer and the side of the bit block, the strain upon the clamping bolt being very materially reduced from previous arrangements, and I have found, by actual experience, that a smaller bolt in the present arrangement will accomplish all that a larger bolt could accomplish in previous arrangements and the bit is more firmly held in its seat.

Having thus described the invention, I claim:-

- 25 1. A bit block for cutter chains comprising a link body having a threaded opening therein disposed at an angle to the vertical axis of said body, a bit carried by the link body, a clamping member engaging the bit and having an opening therein registering with but of greater diameter than the threaded opening, and a clamping screw extending through the opening in the clamping member and engaging the threads of the opening in the link body.
- 30 2. A bit block for cutter chains comprising a link body having a flat upper face pierced by a threaded opening disposed at an angle to the vertical axis of said body, a bit carried by the link body, a substantially wedge-shaped member engaging the bit and having an opening therein registering with but of greater diameter than the threaded opening, the walls of the opening in the clamping member being smooth and unobstructed, and a clamping screw extending through the opening in the clamping member and engaging the threads of the opening in the link body, said screw being provided with an enlarged head bearing against an inclined face of the clamping member.
- 35 3. A bit block for cutter chains comprising a link body having an upstanding abutment and provided with a smooth flat face adjacent said abutment, a holding member bearing against the abutment, a bit fitted to the holding member, said link body being provided with a threaded opening extending through the flat face thereof and disposed at an angle to the vertical axis of the link body, a clamping member engaging the bit and having its lower face flat and engaging the flat face of the link body and its upper face inclined downwardly, there being an opening formed in the clamping

member registering with but of greater diameter than the threaded opening in the link body, a clamping screw extending through the opening in the link body, said clamping screw being provided with an enlarged head, and a washer interposed between the head of the clamping screw and the inclined face of the clamping member.

4. A bit block for cutter chains comprising a link body, a bit carried by the link body, a clamping member slidably mounted on the link body and engaging the bit, and a clamping screw disposed at an angle to the vertical axis of the link body and extending loosely through the clamping member into said link body whereby said screw will exert its pressure at an angle to the cutting face of the bit and cause the clamping member to frictionally engage the link body when the cutting face of the bit engages the work.

5. A bit block for cutter chains comprising a link body, a bit carried by the link body, a clamping member mounted on the link body and engaging the bit, and a clamping screw disposed at an acute angle to the vertical axis of the link body and extending through the clamping member into said link body whereby the impact of the cutting face of the bit with the work will be transmitted through the clamping member to the head of the clamping screw.

6. A bit block for cutter chains comprising a link body, a bit carried by the link body, a clamping wedge mounted on the link body and engaging the bit, and a clamping screw extending through the wedge into the link body and disposed at an acute angle to the line of thrust of the bit when said bit is cutting.

In testimony whereof I affix my signature.
